CLAIM

The ornamental design for a material with bubble pattern, as shown and described.

DESCRIPTION

FIG. 1 is a top plan view of a first embodiment of the material with bubble pattern.

FIG. 2 is a side view of the material with bubble pattern illustrated in FIG. 1.

FIG. 3 is an end view of the material with bubble pattern illustrated in FIG. 1.

FIG. 4 is a bottom plan view of the material with bubble pattern illustrated in FIG. 1.

FIG. 5 is a top plan view of a second embodiment of the material with bubble pattern.

FIG. 6 is a side view of the material with bubble pattern illustrated in FIG. 5.

FIG. 7 is an end view of the material with bubble pattern illustrated in FIG. 5.

FIG. 8 is a bottom plan view of the material with bubble pattern illustrated in FIG. 5; and,

FIG. 9 is a sectional view of the material with bubble pattern illustrated in FIG. 5.

The dot-dash-dot lines depict the boundary of the claim and form no part of the claimed design; whereas, the evenly spaced dots depict environment that is unclaimed.
